SOUND REPRODUCING APPARATUS

Ray E. Tolerton, Fort Wayne, Ind., assignor to
 The Magnavox Company, Fort Wayne, Ind., a
 corporation of Arizona

Application April 6, 1934, Serial No. 719,320

8 Claims. (Cl. 179—115.5)

The present invention relates to electrodynamic sound reproducing apparatus, and more particularly to an improved diaphragm coil and support and method of forming same.

Apparatus of this character usually employs a diaphragm in the form of a truncated cone, to the small end of which there is attached an actuating coil. This actuating coil operates in an annular magnetic air gap which, for maximum efficiency, must have a flux path that is as short as possible. Therefore, it is necessary that the diaphragm actuating coil and its support be constructed with a minimum radial thickness. It is also desirable that the diaphragm coil and its support be of light construction so as not to greatly increase the mass and consequently the inertia of the diaphragm assembly. Considerable difficulty has been experienced in making a diaphragm actuating coil supporting member which would have a minimum thickness and weight and at the same time sufficient strength to withstand the necessary handling, incident to the winding and assembly operations.

Heretofore, a coil support has been formed of a short length of fibre tubing having a peripheral groove cut at one end, into which the coil could be wound. In a later development, the coil support was made entirely of paper wrapped in the form of a tube with additional layers of narrow strips of paper wound thereupon in spaced relation to form coil positioning flanges. These structures were heavy, expensive to manufacture and objectionable because of the thickness necessary for strength.

In United States Patent Number 1,891,404 to Bernard A. Engholm, there is shown a coil support formed of a single thin strip of paper which is embossed so as to provide a cylinder having upstanding ridges for positioning the coil thereupon. In this construction full advantage is taken of the reduction in thickness, thus provided, by threading the ends of the coil through perforations and bringing them out toward the diaphragm across an interior recess formed by the embossing operation. While this construction results in a coil and support assembly having a minimum radial thickness, it involves the tedious and time consuming operation of threading the fine, hair like, coil forming wire through the small openings provided in the support and consequently is expensive and difficult to manufacture.

In order to overcome the above disadvantages, it is an object of this invention to provide a coil supporting member, upon which the coil may be wound in a simple and convenient manner, and

one upon which the coil ends can be effectively secured without threading the fine coil forming wire through perforations in the coil supporting member.

Another object of the invention is to provide a coil supporting member for a diaphragm actuating coil which will have no greater radial thickness than that necessitated by the material forming the supporting member and the layers of wire wound thereupon.

A further object of the invention is to provide a novel method of temporarily securing the ends of the coil upon the coil supporting member during and after the winding operation.

With the above and other objects in view, the invention resides in the construction, combination and arrangement of parts substantially as will be hereinafter described and more particularly defined by the appended claims.

For a better understanding of the invention reference should be had to the accompanying drawing wherein there is shown, by way of illustration and not of limitation, a preferred embodiment thereof.

In the drawing:

Figure 1 is an enlarged view of one side of a coil supporting member constructed in accordance with this invention.

Figure 2 is an enlarged view of the other side of the coil supporting member illustrated in Figure 1, with a portion broken away, and having a coil wound thereupon.

Figure 3 shows a method of attaching the coil supporting member to a diaphragm of the type having an inside coil centering spider, and

Figure 4 shows a method of attaching the coil supporting member to a diaphragm of the type having an outside centering spider.

As shown in Figures 1 and 2 of the drawing, the coil supporting member, designated by the numeral 10, is provided with a raised or embossed portion 11 at its outer end, and embossed portions 12 which are disposed in spaced relation with the embossed portion 11, so as to define a circumferentially extending coil positioning recess 13. The embossed portions 12 extend outwardly from the coil positioning recess 13 along and about the coil supporting member 10, so as to form oppositely extending helical grooves 14 into which ends 15, of a coil 16, may be disposed after the coil has been wound. In addition to the embossed portions 11 and 12, the coil supporting member 10 is shown as having its opposite end enlarged in diameter to provide a diaphragm engaging surface 17.

In constructing the coil supporting member 10, a long tube is first formed by wrapping strips of paper or treated silk or other fabric spirally in overlapping relation about a suitable cylindrical form. This tube is then cut into lengths corresponding to the length of the coil supporting member desired. The length of tube thus cut off is next placed in a die of a character not unlike that disclosed in the Engholm patent cited above.

- 10 This die will have a configuration corresponding to the embossing desired and will form the coil supporting member, as shown in the drawing. After the coil supporting member 10 has been formed in the die it is provided with three notches 18, which are located centrally with respect to the helical grooves 14, and also a pair of spaced notches 19 located in alignment with the outer ends of each of the helical grooves 14. The coil supporting member 10, formed and notched as 15 above, can now be slipped upon a suitable mandrel and wound with the required number of turns of wire to form the coil 16. At the commencement of the winding operation one end 15 of the coil forming wire may be secured to the end of the 20 coil supporting member 10 by cinching it in one of the pairs of notches 19. This wire is then wound helically along the support in the corresponding helical groove 14 to the coil positioning recess 13 where the coil is wound. After the coil 25 16 has been fully wound, preferably with two or an even number of layers of wire, the other end of the coil forming wire is brought out along the remaining helical groove 14 across the previously secured end 15 of the wire and to the other pair 30 of notches 19 where it is cinched to thus secure the coil ends.

From the above, it will be seen that the wire forming the coil 16 can be wound and secured upon the coil supporting member 10 in a simple 40 and convenient manner without requiring any extra wire securing accessory or a threading of the coil ends through perforations in the coil supporting member.

After the coil supporting member 10 has been 45 wound and taken from the mandrel it is coated or dipped, up to the point where the ends 15 of the coil 16 cross, in a suitable hard drying plastic, such as a thin varnish or the like, and allowed to dry. A drying of the varnish or other plastic 50 may be accelerated by subjecting the coil to a baking in a suitable oven. This will firmly secure the coil 16 in the coil positioning recess 13 and the ends 15 thereof in the helically extending grooves 14. Before the coil supporting member 55 10 is secured to a diaphragm the ends 15 of the coil 16 are uncrossed, at the point where the two helical grooves 14 meet, and carried along in spaced relation to the notches 18 where they are secured, as shown in Figures 3 and 4 of the drawing.

When the coil 16 has been wound upon the coil supporting member 10 and its ends secured thereto, as outlined above, it is ready for mounting upon a diaphragm.

60 In Figure 3 of the drawing, the coil supporting member 10 is shown as mounted upon a conical diaphragm 20 which is supported at its small end by means of a so-called inside centering spider 21. The inside centering spider 21 is shown as glued at its periphery in an annular groove 22 formed on the inside surface of the diaphragm 20. At its small end the diaphragm 20 has a cylindrical flange 23 which is adapted to be glued to the diaphragm engaging surface 17 of the coil supporting member 10. When the cylindrical flange 23

is slipped over the end of the coil supporting member 10, the free ends 15 of the coil forming wire will be carried down under the flange 23 and brought up over the outside thereof to fixed terminals 24 which are secured to the outside of the diaphragm 20. The ends 15 of the coil 16 are then connected to an external circuit by means of flexible leads 25 which are attached to the terminals 24.

In Figure 4 of the drawing, the coil supporting member 10 is shown as mounted upon a conical diaphragm 26 which is supported at its small end by a so-called outside centering spider 27. In this arrangement the coil supporting member 10 is secured to the diaphragm 26 in the manner previously described and the outside centering spider 27, which has an annular flange 28, is then slipped over the outside of a flanged portion 29 upon the diaphragm 26 and there secured by a suitable adhesive. The outside centering spider 27 carries terminals 30, to which the coil ends 15 can be soldered, and flexible leads 31, for connecting the coil 16 to an external circuit, extend outwardly from the terminals 30.

Forming of the coil supporting member 10 in 25 the manner described above has the advantage that it is possible to bring out the coil ends 15 without increasing the over all radial thickness of the coil assembly and at the same time secure the ends of the coil during the winding and dipping operations in a simple and convenient manner. Another advantage obtained by the construction described is that after the coil supporting member 10, with its coil 16, has been dipped and secured to the diaphragm the free ends 15 30 of the coil will be firmly and permanently held in spaced relation by the overlying flange of the diaphragm.

From the above it will be seen that by carrying the ends of the coil helically along the support the tension provided in the coil turns during the winding operation can be maintained in a simple and effective manner without requiring any abrupt bending of the coil forming wire, adjacent the coil positioning groove, which might 45 become displaced and release one or more of the end turns of the coil.

While I have, for the sake of clearness and in order to disclose my invention so that the same can be readily understood, described and illustrated specific devices and arrangements, I desire to have it understood that this invention is not limited to the specific means disclosed but may be embodied in other ways that will suggest themselves, in view of this disclosure, to persons 50 skilled in the art. It is believed that this invention is new and it is desired to claim it as such so that all changes as come within the scope of the appended claims are to be considered as part of this invention.

Having thus described my invention, what I claim and desire to secure by Letters Patent is—

1. A coil support for electrodynamic apparatus, comprising a substantially cylindrical member having means defining a coil positioning recess at one end thereof, and having two helical grooves extending from said recess along the outer surface of said cylindrical member and toward its other end into which the coil ends may be disposed.

2. A coil support for electrodynamic apparatus, comprising a substantially cylindrical member having means defining a coil positioning recess at one end thereof, and having two oppositely and helically disposed grooves extending from 75

said recess and along said cylindrical member toward its other end into which the coil ends may be disposed.

3. A coil support for electrodynamic apparatus, comprising a substantially cylindrical member having a coil positioning shoulder thereupon, helically disposed grooves extending through said shoulder and along said cylindrical member into which the coil ends may be disposed, and means at the end of said cylindrical member in line with said grooves to which the coil ends may be secured during the assembly operation.

4. A coil support for electrodynamic apparatus, comprising a substantially cylindrical member having a coil positioning shoulder embossed thereupon, helically disposed parallel ribs extending from said shoulder and along said cylindrical member forming grooves therebetween into which the coil ends may be disposed, and means at the end of said cylindrical member in line with said grooves to which the coil ends may be secured during the assembly operation.

5. A coil unit for electrodynamic apparatus, comprising a substantially cylindrical member having a coil positioning recess at one end thereof, a diaphragm engaging portion at the other end thereof, and having two grooves which originate at the coil positioning recess and extend helically in opposite directions along and around the cylindrical member to the diaphragm engaging portion, a winding in said coil positioning recess having its ends extending in opposite directions in said grooves, and means at the end of said cylindrical member to which the ends of said winding are secured.

6. A coil unit for electrodynamic apparatus, comprising a substantially cylindrical member having a coil positioning recess at one end there-

of, a diaphragm engaging portion at the other end thereof, and having two grooves which originate at the coil positioning recess and extend helically in opposite directions around the cylindrical member to the diaphragm engaging portion, and a winding in said coil positioning recess having its ends disposed in said grooves, said winding and its ends being secured in said coil positioning recess and said grooves by a plastic coating baked thereon after the winding operation.

7. A diaphragm coil supporting form, comprising a substantially cylindrical member of relatively thin construction having an outwardly extending shoulder embossed thereupon for locating a winding at one end thereof, a plurality of helically disposed ridges forming grooves into which the end wires of a coil may be disposed, and means in line with said grooves to which the ends of said winding may be secured during and after the winding operation.

8. An actuating coil unit for electrodynamic sound reproducing apparatus, comprising a cylindrical coil supporting member having one end adapted to be secured to a diaphragm and support a coil in spaced relation therewith, a coil wound upon the other end of said coil supporting member, the ends of the wire forming said coil being brought out and wound spirally in opposite directions about said coil supporting member to a point adjacent its diaphragm engaging end to reinforce said coil supporting member between its coil and diaphragm engaging end, said coil and the spirally wound ends of the wire forming said coil being secured upon said coil supporting member by a hard drying plastic.
